UNITED STATES PATENT OFFICE.

CHARLES F. JACOBS, OF BROOKLYN, NEW YORK.

CLAMPING TERMINAL.

Application filed May 6, 1927. Serial No. 189,318.

This invention relates to clamping devices and has particular reference to an improved device for use as a clamping terminal such as used on storage batteries or the like.

5 Primarily the invention comprehends an improved clamping terminal which insures a positive electrical connection while greatly facilitating the connection or disconnection.

The invention furthermore comprehends 10 an improved clamping terminal of the character set forth which is comparatively simple in its construction and mode of use, which is economical to produce, and which is thoroughly reliable and highly efficient in 15 its purpose.

With the above recited and other objects in view, reference is had to the following description and accompanying drawings in 20 which there is exhibited one example or embodiment of the invention, while the appended claims define the scope of the invention.

In the drawings:

Figure 1 is a perspective view of the 25 clamping terminal as employed in its capacity as a storage battery terminal;

Fig. 2 is a vertical sectional view therethrough taken approximately on the line indicated at 2-2 in Fig. 3;

30 Fig. 3 is a sectional view taken approximately on the line indicated at 3-3 in Fig. 2.

Referring to the drawings by characters of reference, the clamping terminal includes 35 a pair of resilient arms 10 and 11, which are crossed intermediate their length and are formed respectively with clamping jaws 12 and 13 at the free ends, the confronting faces of which are serrated, as indicated at 14 to more effectually grip and establish an electrical connection between the device and 40 a conductor wire terminal 15 or other element with which the device is connected. In order to augment the inherent resiliency of the arms 10 and 11, to effect movement or advancement of the serrated confronting faces 14 with each other, a coiled contractile 45 spring 16 is employed, the opposite ends of which are respectively attached to the crossed portions of the arms adjacent the jaws. To cover, house, and conceal the 50 spring, the jaw 12 is formed with a preferably integral spring housing 17, which is disposed immediately below the jaw 12 and which housing further constitutes a stop or 55 abutment for preventing the forcing of the

wire terminal 15 or other element completely beyond the lower edges of the jaws. The upper corners of the confronting faces of the jaws are rounded off to define a flared entrance mouth 18 which facilitates the engagement of the wire terminal 15 between the jaws. In order to facilitate the spreading or separation of the jaws for removing the wire terminal or other device to be clamped, the jaws 12 and 13 are each provided with a laterally projecting manipulating handle 19 protruding from the opposite sides of the jaws respectively, and which handles are designed to be engaged by the thumb and forefinger.

In use, the wire terminal 15 is grasped in the two hands and forced downwardly through the flared entrance mouth 18 until it is engaged between the serrated confronting faces 14 of the jaws 12 and 13. This immediately establishes a positive and effectual electrical connection and serves to hold the terminal against accidental displacement due to the inherent resiliency of the arms 10 and 11 combined with the auxiliary tension of 80 the spring 16, for normally moving the jaws toward each other and holding the same in a clamping relation. When it is desired to remove the wire terminal 15 from between the jaws, the thumb is engaged with the manipulating handle of the jaw 12 and the forefinger with the manipulating handle of the jaw 13, and pressure is exerted in opposite directions by said thumb and finger to open the jaws.

90 What is claimed is:

1. A clamping terminal for electric conductors including a supporting base, a pair of crossed resilient arms anchored at one end to and straddling said supporting base and having jaws at the free ends provided with confronting normally engaged clamping faces, and a coiled contractile spring connected respectively with the crossed portions adjacent the free ends of said arms for augmenting the normal movement and engagement of the confronting faces of the jaws with each other.

2. A clamping terminal including a pair of crossed resilient arms anchored at one end to a support and having jaws at the free ends provided with confronting normally engaged clamping faces, and a coiled contractile spring connected respectively with said arms for augmenting the normal move-

ment and engagement of the confronting faces of the jaws with each other, one of said arms having a spring housing for said spring located immediately below the inner end of 5 the jaw and underlying the other jaw to constitute a stop or abutment for the element engaged between the jaws.

3. A clamping terminal including a supporting base, a pair of crossed resilient arms 10 anchored at one end to and straddling said supporting base and having jaws at the free ends provided with confronting normally engaged clamping faces, the said jaws respectively provided with a laterally projecting manipulating handle on opposite sides 15

of the jaws respectively for facilitating manual opening of the jaws.

4. A clamping terminal for electric conductors including a supporting base, a pair of crossed resilient arms anchored at one 20 end to said supporting base and having complementary jaws at the free ends provided with confronting normally engaging clamping faces and means immediately below the inner end of one of the jaws and underlying 25 the other jaw to constitute a stop for preventing the passage of the conductor beyond the clamping jaws when engaging the same therbetween.

CHARLES F. JACOBS.
